[57] CLAIM

The ornamental design for an industrial luminaire housing, as shown and described.

DESCRIPTION

FIG. 1 is a side perspective view of an industrial luminaire housing showing our new design;

FIG. 2 is a bottom plan view thereof on an enlarged scale;

FIG. 3 is a front elevational view thereof on an enlarged scale;

FIG. 4 is a rear elevational view thereof on an enlarged scale;

FIG. 5 is a top plan view thereof;

FIG. 6 is an elevational view of the side opposite that shown in FIG. 1;

The refractor is shown in broken lines for illustrative purposes only.
